DESIGN FOR A BUCKLE FOR SHOE

Maxwell M. Babin, Brooklyn, N. Y.

Application August 25, 1934, Serial No. 53,066

Term of patent 7 years

To all whom it may concern:

Be it known that I, MAXWELL M. BABIN, a citizen of the United States, residing in Brooklyn, in the city, county, and State of New York, have invented a new, original, and ornamental Design for a Buckle for Shoes, of which the following is a specification; reference being had to the accompanying drawing, forming a part thereof and in which:

Fig. 1 is a front elevation of a buckle for shoes, showing my new design; and

Fig. 2 is a side view of Fig. 1.

I claim:

The ornamental design for a buckle for shoes substantially as shown.

Signed at New York, in the county of New York and State of New York this 24 day of August, 1934 A. D.

MAXWELL M. BABIN.
